UNITED STATES PATENT OFFICE

147,582

DESIGN FOR AN ADHESIVE TAPE DISPENSER

Donald E. Dailey, Philadelphia, Pa., assignor to Industrial Tape Corporation, a corporation of
New Jersey

Application March 14, 1946, Serial No. 127,489

Term of patent 14 years

(Cl. D74—1)

To all whom it may concern:

Be it known that I, Donald E. Dailey, citizen of the United States, residing in Philadelphia, in the county of Philadelphia and State of Pennsylvania, have invented a new, original, and ornamental Design for an Adhesive Tape Dispenser, of which the following is a specification, reference being had to the accompanying drawings, forming part thereof.

Figure 1 is a side elevational view of an adhesive tape dispenser showing my new design, the opposite side presenting substantially the same appearance as the side shown.

I claim:

The ornamental design for an adhesive tape dispenser, as shown and described.

DONALD E. DAILEY.
